UNITED STATES PATENT OFFICE.

CHRISTIAN SHIVELY, OF CARNEGIE, PENNSYLVANIA, ASSIGNOR TO THE DILWORTH, PORTER & COMPANY, LIMITED, OF PITTSBURG, PENNSYLVANIA.

METHOD OF MAKING RIBBED PLATES.

SPECIFICATION forming part of Letters Patent No. 650,873, dated June 5, 1900.

Application filed December 7, 1899. Serial No. 739,565. (No model.)

To all whom it may concern:

Be it known that I, CHRISTIAN SHIVELY, a citizen of the United States, residing at Carnegie, in the county of Allegheny and State 5 of Pennsylvania, have invented or discovered certain new and useful Improvements in Bars for Tie-Plates, of which improvements the following is a specification.

The invention described herein relates to 10 certain improvements in the manufacture of plates having ribs on one side, such as tie-plates for use under rails, and has for its object the shaping of an ingot or billet by successive passes through suitable rolls or by other 15 suitable means into a bar or blank having ribs along one side and with flanges along its edges extending beyond or outside of the ribs.

In general terms the invention consists in displacing, by the action of suitably-shaped 20 rolls or by other suitable means, the metal along the middle portions of the opposite sides of an ingot or billet, thereby forming two pairs of ribs projecting from opposite sides of the body portion of the bar, gradually increasing the relative height of one pair of 25 ribs by further displacement of the metal of the middle portion of the bar until the thickness of the body portion has been reduced to or approximately to that of said ribs, and simultaneously inclining or beveling one or 30 both walls of the other pair of ribs, and finally spreading out the first pair of ribs into the plane of the body portion, thereby forming flanges projecting beyond or outside of the 35 ribs having the inclined or beveled sides.

The invention further consists in rolls having passes, as hereinafter more fully described and claimed.

In the accompanying drawings, forming a 40 part of this specification, Figure 1 is a view in elevation of rolls having a portion of the passes constructed for rolling tie-plates in accordance with my improvement, and Fig. 2 is a similar view showing rolls having the 45 final passes.

In the practice of my invention the first pass A of the rolls is so shaped or constructed that the metal along the middle portion of the opposite sides of the ingot or billet is displaced, portions of the displaced metal flowing laterally and vertically to form ribs a a

and b b along the edges on opposite sides of the ingot or billet. The second, third, and fourth passes B, C, and D are so shaped or constructed as to continue the reduction of the 55 body portion c in thickness, thereby increasing the projection of the ribs from the body. The thickness of the ribs a a is not affected in these passes except in so far as may be necessary to obtain the required draft to 60 elongate the ribs equally with the body portion. The portions of the surfaces of the rolls operating on the inner walls of the ribs b b are constructed to impart a bevel or incline to said walls, thereby reducing the thickness 65 of the edges of said ribs at each pass. The fifth pass E is so constructed as to reduce the thickness of the body portion c to or approximately to that of the ribs a a and also to effect a working or bending of the ribs outward, so that they will be at an angle greater 70 than a right angle to the body portion. The sixth pass is constructed to work the ribs a a outward and down into the plane of the body portion and preferably without any material 75 reduction of thickness beyond that incident to giving the rolls the bite on the article necessary to move it through the rolls. In this pass the outer walls of the ribs b b are also beveled or inclined, so as to give such ribs a 80 symmetrical wedge shape in cross-section. The last pass is constructed to work or bend the ribs a a into alignment with the body portion c, forming flanges or lateral extensions of the bar or blank. 85

It will be understood by those skilled in the art, that the number of passes, in the shaping of the ingot or billet to the completed bar, may be varied by changing the dimensions of the passes in the roll, and the 90 height of the ribs may be changed as desired by changing the depth of those portions of the passes in which the ribs are formed, without departing from the spirit of my invention.

It is characteristic of my method that the 95 directions of the flow of metal in all passes is not materially different from that originated in the first pass, and hence the resulting bar is free from all injurious strains. It is also characteristic of my improvement that the 100 projection of the flanges beyond the ribs and the depth of the latter can be regulated at

will. It is further characteristic of my improved method that a greater projection of the flanges can be obtained than in any of the methods now in use.

5 I claim herein as my invention—

1. As an improvement in the art of forming bars for ribbed plates, the method herein described, which consists in rolling up and down oppositely-projecting ribs on opposite 10 sides of a bar and then bending the ribs of one side of the bar out and into alinement with the body of the bar, substantially as set forth.

15 2. As an improvement in the art of forming bars for ribbed plates, the method herein described, which consists in displacing the metal along the middle portions of opposite sides of an ingot or billet, causing portions of the displaced metal to flow outwardly and 20 vertically, thereby forming ribs on opposite sides of the body portion of the article and finally bending the ribs of one side of the

body out and into alinement with the body, substantially as set forth.

3. As an improvement in the art of forming bars for ribbed plates, the method herein described, which consists in displacing the metal along the middle portions of opposite sides of an ingot or billet, causing portions of the displaced metal to flow outwardly and 30 vertically, continuing the displacement of the metal along such middle portions and simultaneously inclining or beveling the side walls of the ribs on one side and finally bending the ribs on the opposite side out and into alinement with the body portion, substantially as set forth.

In testimony whereof I have hereunto set my hand.

CHRISTIAN SHIVELY.
